UNITED STATES PATENT OFFICE

147,629

DESIGN FOR A TOY FISH OR SIMILAR ARTICLE

Constance Ray White, Beverly Hills, Calif.

Application December 26, 1946, Serial No. 135,752

Term of patent 14 years

(Cl. D34—2)

To all whom it may concern:

Be it known that I, Constance Ray White, a citizen of the United States, residing at Beverly Hills, in the county of Los Angeles and State of California, have invented a new, original, and ornamental Design for a Toy Fish or Similar Article, of which the following is a specification, reference being had to the accompanying drawing, forming part thereof.

In the drawing:

Fig. 1 is a side view of a toy fish showing my new design;

Fig. 2 is a top view thereof, and Fig. 3 is a front view thereof.

I claim:

The ornamental design for a toy fish or similar article, substantially as shown.

CONSTANCE RAY WHITE.
